UNITED STATES PATENT OFFICE

JULIUS R. WEMLINGER, OF NEW YORK, N. Y.

CORRUGATED SHEET PILING

Application filed January 20, 1930. Serial No. 422,155.

This invention relates to corrugated sheet metal piling of the type covered by my Patent No. 1,166,563, of January 4, 1916, and has for its object certain new and useful improvements thereto.

As in the said patent, the present piling consists of long and narrow sections or piles, which are corrugated longitudinally and so constructed that adjacent sections can be interlocked by lateral engagement of their edges. In the present piling, however, the corrugations are semi-circular throughout, the tangents 6 of my said patent being omitted. The radii of the corrugations are equal except those of the marginal ones, which are shorter than the radii of the central or body corrugations. Thus, the radii of the latter may be $1\frac{1}{8}$ in., while the inside radius of one of the marginal corrugations is $\frac{5}{8}$ in. and the outside radius of the other marginal corrugation is $\frac{5}{8}$ in., so that the marginal corrugations of adjacent sections will fit snugly together. The advantages of this construction are: the over-all width of the piling section is reduced while the effective width remains the same, whereby the weight and cost are reduced; by the effective width is meant the distance between center lines of the marginal corrugations of a section; and the edges of the sections are more rigid owing to their smaller radii. This is an important improvement, since it happens frequently that the edges become bent or distorted in handling, whereby the joining of adjacent sections is rendered difficult or even impossible. In some cases, I may form a bead on the edges to further stiffen them. In the present piling, I make use of clips secured near one edge of each section to interlock it with the adjacent section, as in my said patent. But difficulty has been encountered with the clips of the patent by reason of their being bent back and it is not desirable to use heavier metal on account of the increased weight and cost. In the present form of the piling, I use similar clips but reinforce them by one or more ribs formed on their back. With these ribs, the clips can be made of the same thickness as the rest of the piling and

yet will be stiff enough to retain their shape permanently.

The invention is illustrated in the accompanying drawing, in which,

Fig. 1 is a plan view of one section and the 55 marginal edges of the two adjoining sections;

Fig. 2 is a front view of the same, partially broken away, and

Fig. 3 is a detail plan view of the interlocking edges of two sections, showing a 60 slight modification.

Each section is formed with the semi-circular longitudinal corrugations 2 throughout the major portion of its width and with the marginal corrugations 3 and 4, also semi-circular but of shorter radii, as above explained. The corrugation 3 of one section fits within the corrugation 4 of the adjoining section. To form the interlock, two or more clips 5 are secured, preferably by electric welding, to each section adjacent its marginal corrugation 4. The curved tongues of these clips lie within the corrugation 4, as in my said prior patent. Each clip has one or more, two in the form shown, reinforcing ribs 6, formed on its back for the purpose stated.

In Fig. 3, the extreme edges of the sections are shown as thickened, or provided with a bead 7, to give them additional stiffness. 80

Having thus described my invention, what I claim is:

Corrugated sheet piling having the marginal corrugations of lesser radius than those of the main body, and interlocking clips, 85 having stiffening ribs on their backs, secured to the body adjacent one of the marginal corrugations, as and for the purpose described.

Signed at New York, in the county of New 90 York and State of New York, A. D. 1930.

JULIUS R. WEMLINGER.
